US0D1052601S

(12) **United States Design Patent** (10) Patent No.: **US D1,052,601 S**
(45) Date of Patent: ** Nov. 26, 2024

(54) **DISPLAY SCREEN OR PORTION THEREOF WITH A GRAPHICAL USER INTERFACE FOR SEARCHING DIGITAL CONTENT**

(71) Applicant: **Buzz Capital Inc.**, Santa Monica, CA (US)

(72) Inventor: **Mohamed Rostom**, Santa Monica, CA (US)

(73) Assignee: **Buzz Capital Inc.**, Santa Monica, CA (US)

(**) Term: **15 Years**

(21) Appl. No.: **29/874,442**

(22) Filed: **Apr. 19, 2023**

(51) LOC (14) Cl. **14-04**

(52) U.S. Cl.

USPC **D14/485**

(58) **Field of Classification Search**

USPC **D14/485-495**
